FIRE CONTROLLING MECHANISM FOR
AUTOMATIC FIREARMS

George William Patchett, Chigwell, England

Application November 27, 1943, Serial No. 512,004
In Great Britain August 17, 1942

10 Claims. (Cl. 89—142)

1

This invention relates to the trigger and fire-controlling mechanism of automatic firearms, and although more particularly applicable to those firearms which fire on the forward stroke of the bolt and in which the bolt recoils against a spring after the cartridge has been fired, it is not necessarily limited to such application.

In some automatic weapons of the type set forth there is a tendency for the firearm when fitted with a charged magazine to discharge a round involuntarily if subjected to sudden shock, whilst in use the general balance and control of the weapon may leave much to be desired.

The object sought to be achieved is to overcome the above disadvantages and to render the firearm immune from the liability to discharge a round if subjected to sudden shock, to render the whole of the trigger, sear and fire control mechanism removable as a complete unit for cleaning and adjustment, and to provide a better means whereby the weapon can be placed into a safe, or inoperative condition, or into a semi-automatic or fully automatic condition for use.

This invention consists in the manufacture of an automatic firearm having in combination a trigger operated pivoted sear actuating member, a sear pivoted coaxially with said actuating member pivot, a sear controlling lever pivoted on said sear actuating member, said controlling lever engaging said sear under spring pressure unless displaced about its pivot by a selector device mobile at will to determine the safe or either of two firing conditions.

With the above arrangement the trigger and sear pivots are disposed forward of the bolt and/or firing pin when the latter are in the cocked position, which arrangement enables a better balance to be given to the weapon and a better functioning of the recoiling masses during the firing operation.

The invention is further characterized that the trigger and sear mechanism are so mounted as to be a readily removable unit, for the purposes of cleaning and adjustment.

To enable the invention to be better understood reference is made to the accompanying drawings wherein a preferred embodiment of the invention is illustrated, and wherein—

Fig. 1 is a part sectional vertical elevation of the firearm showing the selector device set at the safe position.

Fig. 2 is an enlarged view of the trigger and selection mechanism.

Fig. 3 is an end view of Fig. 2 from the direction of arrow, line 3—3, Fig. 2.

2

Fig. 4 shows the removable trigger and sear mechanism as a unit, and the part of the firearm with which the unit is directly associated.

Referring to the drawings and to Figs. 1, 2 and 5 3 the rifled barrel 1 is connected to the receiver 2, in which latter is housed a cocking handle 4, the bolt 3 and a firing pin 5. The main recoil spring 6 is held under compression between the bolt 3 with firing pin 5 and the end cap 7. Beneath the receiver 2 and approximately centrally of its length is the trigger 8. The said trigger is formed with arcuate wiper guards 9 and is pivoted upon a pin 10 mounted in and extending between a pair of trigger plates 28, the said trigger being pressed to its normal or idle position by a spring-loaded plunger 11, the latter taking an abutment against a pin or the like 12 extending between two sear actuating plates 15 pivoted on a pin 17 carried by the pair of trigger plates 28. The trigger 8 adjacent its pivot pin 10 contacts upon movement with a roller 13 mounted on a pin 13a extending between the sear actuating plates 15. When the said trigger 8 is pulled its face 14 lifts the roller 13, and when released the face 16 of trigger 8 comes to rest in its original position on the roller 13, as shown in Fig. 2. The sear actuating plates 15 are formed as two counterpart cheeks tied and distanced by pillars constituted by stop pin 12, the pivot pin 13a of the roller 13 and other transverse pins or pillars of the mechanism. Between the said sear actuating plates 15 is disposed the sear 18 on pivot pin 17, having a sear face 18a, a slotted tail piece 18b, a stop 18c engaging the receiver 2 and a part 18d engaging pivot pin 19b of the sear actuating lever 19. The sear actuating lever 19 is adjacent to the sear and has a cross head 20, said cross head (see Fig. 3) embracing or otherwise guiding the split tail pieces 18b of the sear 18. The sear 18 is pressed upwards towards the bolt race 2a by a spring-loaded plunger of normal design 21, the said plunger contacting with the arm 19a of sear actuating lever 19. The sear is pivoted upon pin 17, this pivot pin and the pivot pin 10 of the trigger 8 being positioned forward of the face 3a of bolt 3 while the bolt is in the cocked position, at which time the forward face of the bolt will occupy the position indicated by the dotted line A in Fig. 1. The sear actuating lever 19 is pivoted 40 between the sear actuating plates 15 and is provided with a projection 22 adapted to engage the top of the selector cam 23 when the selector cam is set to "safe" as shown in dotted lines at B in Fig. 2. The said cam is mounted rigidly upon 45 a mobile shaft 24 and operated by a selector 50 55

lever 25 disposed on the outside of the gun and aft of, but adjacent to the trigger 8. The selector lever 25 is fast with shaft 24 and by undercutting as at 25b is slightly flexible, and is provided at its terminal 25a remote from shaft 24 with a ball 26, adapted to engage one of three recesses 27 formed in the side plate 35 of the trigger housing. The said recesses 27 correspond with and control the predetermined angular positions of the selector cam 23, which latter is capable of being set at will to "safe" at B corresponding to the position of selector lever 25 at S, "semi-automatic" C corresponding to the position of lever 25 at R and "full automatic" D corresponding to the position of lever 25 at A in Fig. 4. The total movement of the selector cam 23 is limited by stops 29. The said selector cam 23, at the three determined positions engages respectively: in the "safe" B position, the projection 22 of the sear actuating lever 19; in "semi-automatic" C position, the underside of the actuating lever arm 19a; and disengages from any contact with the sear actuating lever 19 when set in D position for "full automatic" or continuous firing.

A removable magazine (not shown) is provided for insertion in the magazine holder 30 (Fig. 4) on receiver 2 and hence is at right angles to the plane of the hand grip 32.

Fig. 4 shows the trigger 8 and associated parts as a removable entity and capable of extraction from the gun by the withdrawal of the locking pins 34 which are removably inserted through trigger plates 28 and a pair of trigger box housing plates 35 fixed to the receiver. In this condition the assembly can be cleaned and replaced in a few minutes.

The operation of the invention is as follows:

Assuming the breech to be closed as shown in Fig. 1 and the selector lever at safe position, i. e. B. Fig. 2, the first action is to set the selector lever 25 to either of the positions C or D and then to cock the bolt 3, by operating the cocking handle or equivalent 4, which causes the bolt and firing pin to traverse backwards until the bolt has passed the sear 18 at position A, Fig. 1. The bolt 3 depresses the sear 18 at the beginning of its movement backwards, the sear tail piece 18b contacting the pivot pin 19b of the sear actuating lever, thereby causing the sear actuating plates 15 to pivot about the pin 17, compressing the spring of the plunger 11. After the bolt has passed the sear face 18a the spring plunger 11 returns the sear mechanism to position shown in Fig. 2, obstructing the return path of the bolt.

Assuming the selector cam 23 is set to semi-automatic, in position C, the trigger is pulled and its shoulder 14 contacts with the roller 13 rotating the sear actuating plates 15 upon pivot pin 17, which has the effect of withdrawing the sear face 18a of the sear 18 out of the path of the bolt 3 and causing the sear actuating lever arm 19a to engage the selector cam 23, as at C. Since further movement downward of said arm 19a is impossible, the sear actuating lever 19 rotates about its pivot pin 19b compressing the spring of plunger 21 and immediately after the sear face 18a has released the bolt 3, the crosshead 20 disengages from the upper face of the sear tail-piece 18b and releases the sear 18 to pivot on the pin 17 under urge of the spring of plunger 21 and regain its original position with the stop 18c engaging the receiver after the bolt has recoiled beyond the cocked position. During this movement and although the crosshead 20 of the sear actuating lever 19 has disengaged from

the upper face of the sear tail-piece 18b, the said tail-piece 18b still remains in a guided relation to the sear actuating lever 19, since the lower sear parts 18d still embrace the sear actuating lever 19.

Hence upon such trigger movement the bolt is released by the sear and under urge of the spring 6 moves forward to close the breech and fire the cartridge, which in the forward movement of the bolt has been caused to enter the barrel 1, in the known manner. The recoil pressure of firing returns the bolt 3 and striking pin 5 against the pressure of the spring 6, beyond the sear 18, which latter having been released by the crosshead 20 returns to its position akin to that shown in Fig. 2, to arrest the bolt 3 on its then forward movement, even though the trigger is still held back. Hence only a single shot is fired and the bolt is held arrested in the cocked position. During this bolt movement the spent cartridge has been withdrawn by the extractor (not shown) and ejected, whilst a new cartridge has been fed forward to the mouth of the magazine, ready to enter the breech of the barrel upon the return of the bolt. So long as the trigger is squeezed nothing further happens, and a single shot only has been fired. If the trigger is released the abutment 14 is withdrawn from the roller 13, the spring plunger 11 operates to return the sear plates to their original position as shown in Fig. 2, the spring plunger 21 causing the sear actuating lever 19 to also return to its original position, wherein the crosshead 20 again engages the tail-pieces 18b of the sear 18. It will be noted that despite the relative motion between the sear actuating plates and the sear the sear actuating lever arm 19 never actually leaves the slotted tail-piece 18b of the sear 18. Re-actuation of the trigger repeats the operation and again a single shot is fired.

To set the weapon to full continuous automatic firing the selector lever 25 is set so that the selector cam 23 assumes position D, see Fig. 2, and pressure on the trigger 8 will disengage the sear 18 from the bolt 3 as previously described, but as the downward movement of the sear actuating lever arm 19a is not arrested by the selector cam 23, the crosshead 20 of the sear actuating lever 19 remains in engagement with the sear tail-piece 18b maintaining the sear below, and therefore no longer obstructing, the path of the bolt. Hence on actuation of the trigger, the bolt moves forward and fires the cartridge, is driven rearwards by the cartridge recoil, and forwards again by the spring 6, and so on until the trigger is released or the ammunition supply ceases.

If the selector cam 23 be moved to position B, i. e. at "safe," while the bolt is uncocked, the sear and associated parts lock the bolt forward as shown in Fig. 1, thus preventing the bolt being jolted back to pick up and fire a cartridge accidentally. If the bolt 3 is cocked and the selector cam 23 then set to "safe," the bolt is locked against forward movement by the sear 18 engaging the face 3a of the bolt, and further the trigger, if pulled, cannot rotate the sear actuating plates 15 owing to the projection 22 of the sear actuating lever 19 contacting the selector cam 23 at position B. Since in these positions the sear is positively locked from all movement, no accidental shock or bolt can displace it, and allow firing to take place.

It will be observed that the trigger and sear pivots are disposed substantially midway between the limits of operational traverse of the mobile bolt 3.

I claim:

1. A firearm comprising a receiver, a breech bolt reciprocable therein, and sear mechanism including a sear actuating member pivotally mounted in the receiver, a sear pivotally mounted in the receiver coaxially of the pivot of said member for holding the bolt in cocked position and retractable to release the bolt, a sear actuating lever pivoted on the sear actuating member eccentrically of the pivotal axis of said member and rotatable into positions to retract the sear from the bolt and to release the sear, means for yieldingly urging said actuating lever into position to release the sear, a trigger pivoted in the receiver and operative when manually operated to move the sear actuating member and the sear actuating lever in a direction to retract the sear, the sear actuating lever having an arm thereon extending radially from its pivotal axis, and a selector device movable into a position to be engaged by said arm on the sear actuating lever and thereby cause rotation of the latter on its axis in a direction to release the sear when the sear actuating member is operated by manual operation of the trigger.

2. A firearm comprising a receiver, a breech bolt reciprocable therein, and sear mechanism including a sear actuating member pivotally mounted in the receiver, a sear pivotally mounted in the receiver for holding the bolt in cocked position and retractable to release the bolt, a trigger pivoted in the receiver and engageable with the sear actuating member to operate the latter when the trigger is manually operated, a lever pivotally mounted on the sear actuating member and rotatable into positions to retract the sear from the bolt and to release the sear, said lever having an arm projecting radially therefrom, means interposed between said arm and the sear for yieldingly urging the sear toward bolt cocking position and said lever toward retracting relation with the sear, and a selector device movable into the path of said arm, when the sear actuating member is operated by manual operation of the trigger, to obstruct said arm and thereby rotate said lever in a direction to release the sear.

3. A firearm comprising a receiver, a breech bolt reciprocable therein, and sear mechanism including a sear actuating member pivotally mounted in the receiver, a sear pivotally mounted in the receiver coaxially of the pivot of said member for holding the bolt in cocked position and retractable to release the bolt, a trigger pivoted in the receiver and engageable with the sear actuating member to operate the latter in sear retracting direction when the trigger is manually operated, a lever pivotally mounted on the sear actuating member and having a pair of arms one of which is engageable with the sear to retract it and thereby release the bolt, a spring interposed between the other arm and the sear and acting to urge the sear toward bolt cocking position and the first-mentioned arm into a position to retract the sear, and a selector device movable into a position in the path of said other arm to obstruct its movement and thereby rotate said lever on its pivotal axis in a direction to release the sear when the trigger is manually operated.

4. A firearm comprising a receiver, a breech bolt reciprocable therein, and sear mechanism including a sear actuating member pivotally mounted in the receiver, a sear pivotally mounted coaxially of the pivot of said member for holding the bolt in cocked position and retractable to

release the bolt, a trigger pivotally mounted in the receiver and engageable, when manually operated, with said member to operate the latter in a direction to retract the sear and thereby release the bolt, a lever pivotally mounted on the sear actuating member and having a sear retracting arm engageable with and releasable from the sear by rotation of said lever, said lever having a controlling arm extending therefrom, a spring interposed between said controlling arm and the sear for urging the latter toward bolt cocking position and for urging said retracting arm on said lever into a position to retract the sear, and a selector device movable into a position to obstruct movement of said controlling arm and thereby cause rotation of said lever on its pivot to release said lever from the sear, and movable into another position to obstruct operation of the sear actuating member by the trigger and thereby lock the sear from retraction.

5. An automatic firearm comprising a receiver, a breech bolt reciprocable therein, a sear pivoted in the receiver for holding the bolt in cocked position and retractable to release the bolt, a sear actuating member pivotally mounted in the receiver, a trigger pivotally mounted in the receiver to engage said member and to operate it in sear retracting direction, a lever having a pivot mounting it on said member, said pivot being engageable with the sear, a sear retracting arm on said lever engageable with the sear and releasable therefrom by rotation of said lever on its pivot, a controlling arm on said lever, a spring between the controlling arm and the sear for urging the latter toward bolt cocking position and urging the lever to rotate on its pivot to engage the sear, and a selector member movable into a position to obstruct movement of the controlling arm and thereby rotate the lever to release the retracting arm from the sear when the trigger is pulled, and movable into a second position to obstruct movement of said sear actuating member by pulling the trigger and thereby hold the pivot of said lever against the sear to lock the latter from retraction, and movable into a third position clear of said lever and member and thereby free the sear for retraction by the trigger and hold the sear retracted by said member and lever when the trigger is pulled.

50 6. An automatic firearm as defined in claim 5, wherein said bolt is provided with means engageable by said sear for retaining the bolt in either its closed or its cocked position, and said selector device when moved into said second position locks said sear in retaining relation with said bolt while the latter is in one or the other of said positions.

55 7. An automatic firearm as defined in claim 5, wherein said selector device comprises a shaft rotatably mounted in said receiver and carrying an arm movable by rotation of said shaft into different angular positions.

8. An automatic firearm comprising a receiver, a breech bolt reciprocable therein, a sear pivoted in the receiver for holding the bolt in cocked position and retractable to release the bolt, the sear having a split tail-piece, a sear actuating member pivotally mounted in the receiver, a trigger pivotally mounted in the receiver and operative, when pulled, to engage and move said member in sear retracting direction, a lever pivotally mounted on said member and having a sear retracting arm embraced and guided by the split tail-piece of the sear and engageable with and releasable from said tail-piece by rotation of said

70 lever on its pivotal axis, a controlling arm on said

lever, a spring interposed between the controlling arm and the sear and acting to hold the retracting arm of the lever in retracting relation with the sear and to hold the sear in bolt cocking position, and a selector member movable into the path of said controlling arm, when the sear actuating member is operated by pull of the trigger, to obstruct movement of said controlling arm and thereby cause rotation of said lever on its pivotal axis to release the sear, said selector member being movable into another position to clear said controlling arm and thereby enable said spring to retain said retracting arm in retracting relation with the sear while the trigger is pulled.

9. A firearm comprising a receiver, a sear pivotally mounted therein, a sear actuating member pivotally mounted in the receiver coaxially with the sear and having a pair of projections thereon located in different angular positions around its pivotal axis, means carried by said member for retracting the sear, a trigger pivotally mounted in the receiver and having a recess therein to receive one of said projections, said recess having a wall engageable with the projection therein to move said member in sear retracting direction when the trigger is pulled, said recess having another wall engageable with the projection therein to stop the return movement of the trigger, and a spring interposed between the trigger and the other projection on said member and acting to return the trigger to its normal position and to return the sear to its cocking position.

10. A firearm as defined in claim 9, wherein said projection in said recess in the trigger comprises a roller having rolling contact with said walls of said recess.
